DOOR LATCH

Fred M. Schultz, Detroit, Mich.

Application February 13, 1939, Serial No. 256,047

14 Claims. (Cl. 292—273)

My invention relates to a new and useful improvement in a door latch adapted for being mounted on a door or other swingable closure, and so arranged and constructed that when moved to one position it will serve as an effective lock for preventing swinging movement of the door, and when moved to another position will permit the swinging of the door a predetermined distance and prevent its further swinging into open position, and when moved to another position will permit the free and customary swinging of the door.

It is an object of the present invention to provide a latch of this type which will be simple in structure, economical of manufacture, durable, compact, light, easily and quickly installed, and highly efficient.

Another object of the invention is the provision of a latch of this class so constructed and arranged that it may be easily and quickly moved into position for permitting a slight open swinging of the closure and easily and quickly moved from this position of operation to a position where it will serve as an effective bar against open swinging of the closure.

Another object of the invention is the provision of a latch of this class having a slot-bearing plate cooperating with a retaining bolt, the relative structure of the slot and the bolt being such that the bolt may be swung out of operative engagement with the slot only when the closure is in fully closed position.

Another object of the invention is the provision in a latch of this type of means for retaining the retaining bolt in locked position when moved thereto.

Other objects will appear hereinafter.

The invention consists of the arrangement and combination of parts hereinafter described and claimed.

The invention will be best understood by a reference to the accompanying drawing which forms a part of this specification, and in which:

Fig. 1 is a front elevational view of the invention showing it applied.

Fig. 2 is a top plan view of the invention showing it applied.

Fig. 3 is a sectional view, slightly enlarged, taken on line 3—3 of Fig. 1.

Fig. 4 is a view similar to Fig. 2 showing the retaining bolt moved to inoperative position.

Fig. 5 is a top plan view illustrating the invention used with the closure partially open.

Fig. 6 is a fragmentary, sectional view through the supporting lugs showing the retaining bolt

swinging across center to inoperative position.

Fig. 7 is a perspective view of the latch plate used in the invention.

Fig. 8 is a plan view of the blank from which the latch plate is made.

In the drawing, I have illustrated the invention associated with a door or swingable closure 14 swingable relatively to a stationary part 15. The invention comprises a plate 16 having an elongated slot formed inwardly from one end thereof, 10 the side walls 17 and 18 of this slot being struck on an arc to provide the inner-wide portion and the constricted neck 19. At the opposite end, the plate 16 is slotted along the lines 20 and 21 and a portion of the center tongue 22 is cut away 15 to provide the oppositely disposed side tongues 23 and 24, which extend beyond the end of the center tongue 22. These side tongues 23 and 24 are pressed outwardly and curved, as shown in Fig. 7. The slotted end of the plate 16 is also 20 curved outwardly in the same direction, as are the tongues 23 and 24. Openings 25 are formed in the plate 16 through which screws or other suitable fastening means may be projected for securing the plate 16 to the swingable closure 14. 25

Secured by screws or in any other suitable fastening manner to the stationary part 15 is a plate 27 projecting outwardly from which are the spaced lugs 28 and 29 between which is pivoted by means of the pin 30 one end of a retaining bolt or bar. This bolt or bar is formed trough-shape with side walls 33 and 34 projecting outwardly from a bottom 32 which forms the back or outer side of the bar or bolt. These side walls are cut away toward the forward end of the bar or bolt and at their rearward ends they are provided with slots 35, the slots in the opposite side walls being in alignment. The pin 30 projects through these slots. Punched inwardly from the bottom 32 is a tongue 36 to 40 which one end of a spring 37 is attached, the opposite end thereof being secured to the pin 39 so that the spring normally tends to maintain this bolt or bar thrust rearwardly so that the pin 30 is in engagement with the center of the 45 slots 35. Projected laterally outwardly from opposite ends from the forward ends of this bar or bolt are the arms 38 and 39 which provide a cross-head of substantially the same diameter as the arc on which the tongues 23 and 24 are 50 struck.

As clearly shown in Fig. 1, the bar or arm tapers abruptly at its rear end to provide a portion of considerably less width than the remaining portion. This narrowed portion of the bar 55

or arm is of such width that it may freely pass through the constricted portion 19 of the slot in the plate 16. The end of the slot which is wider is of such width that the thicker portion of the 5 bar or bolt may freely slide therein.

When the parts are mounted in the relative operative position shown in Fig. 1 the lock bar may be swung on its pivot and when it is moved longitudinally against the tension of the spring 10 36 until the pin 30 is in engagement with the rear end of the slots 35 the narrowed portion A of the lock bar may freely pass downwardly through the narrowed portion of the slot formed in the plate 16 and after passage through this 15 slot a release of the longitudinal thrust on the lock bar or bolt will permit the spring 36 to move the lock bar or bolt rearwardly until the pin 30 engages the forward ends of the slots 35. In this way, the position shown in 20 Fig. 2 is arrived at. When in this position, the narrowed portion A is moved rearwardly so that the wider portion of the bar is engaging in the slot. Consequently, a swinging outwardly of the bar on its pivot is prevented so that when the 25 structure is in the form shown in Fig. 2 undue opening of the closure cannot be effected by thrusting an article through the space 26 between the swingable closure 14 and the stationary part 15. When the device is in the position shown 30 in Fig. 2, upon a swinging of the closure 14 to open position, the plate 16 will ride along the bar or bolt until the arms 38 and 39 engage the angularly turned portions of the plate 16 whereupon further swinging of the closure will be 35 prevented. In this manner, the device will be used to permit the swinging of the closure to open position a predetermined distance and definitely limiting its swinging movement to this predetermined distance.

40 From the position shown in Fig. 2 the bar or bolt may be moved longitudinally against the tension of the spring 36 until the pin 30 is engaging the rear end of the slots 35 and then the cross-head may be dropped downwardly 45 behind the lugs 23 and 24. The spring will retain the arms 38 and 39 in snug engagement with the lugs 23 and 24 and the door will thus be locked in closed position. In order to release the structure from this locking position, 50 it is but necessary to exert longitudinal pressure on the bolt or bar so as to move the arms 38 and 39 clear of the lugs 23 and 24, whereupon the structure may be moved to the position shown in Fig. 2.

55 Thus the device serves to effectively lock the closure against swinging movement from fully closed position and also locks the closure against swinging movement to open position after it has been swung a certain distance. With a device 60 of this kind, it thus becomes possible to open a door a slight distance sufficient to permit conversation and observation through the slightly opened door, while preventing entrance of a person's body through the partly opened door.

65 It will be noted that the bar or arm is so pivoted on the tongues 28 and 29 that when swung into vertical position in moving to the position shown in Fig. 4, the bar or arm would 70 have to be moved longitudinally against the compression of the spring in order to pass center. Consequently, when this bar or arm is swung into position shown in Fig. 4, accidental swinging of the arm accidentally shown in Fig. 2, is prevented, 75 so that it is not possible for the device to acci-

dentially lock a person out of a room by swinging accidentally into position shown in Fig. 2.

The device, in addition to being durable and cheaply manufactured, as well as attaining all of the advantages enumerated, is one which lends 5 itself to ornamentation, so that its presence on a door and a door jam does not mar the appearance of a room in which used.

It is recognized that there may be a few modifications and changes in the structure which would suggest themselves without departing from the scope of the invention, and it is the intention to include such variations and departures from the structure illustrated within the claims which are attached herewith and which form a part 15 hereof.

What I claim as new is:

1. A device of the class described adapted for use with a swingable closure mounted adjacent a stationary part; a plate mounted on said swingable part and comprising; a pair of spaced members projecting outwardly of said swingable part adjacent one end of said plate, the space separating said members being constricted toward the outer end thereof; a latch bolt pivotally mounted adjacent one end to said stationary part and having a narrowed portion adjacent its pivoted end of sufficiently small dimension for passage through the constricted portion of said space, the remaining portion of said latch bolt 30 being of greater width than the width of the constricted portion of said space and freely slideable in said space below the constricted portion; and abutment means for engaging said spaced-apart members upon swinging of said closure the 35 length of said bolt.

2. A device of the class described adapted for use with a swingable closure mounted adjacent a stationary part; a plate mounted on said swingable part and comprising; a pair of spaced members projecting outwardly of said swingable part adjacent one end of said plate, the space separating said members being constricted toward the outer end thereof; a latch bolt pivotally mounted adjacent one end to said stationary 40 part and having a narrowed portion adjacent its pivoted end of sufficiently small dimension for passage through the constricted portion of said space, the remaining portion of said latch bolt 45 being of greater width than the width of the constricted portion of said space and freely slideable in said space below the constricted portion; abutment means for engaging said spaced-apart members upon swinging of said closure the 50 length of said bolt; and means on said closure 55 engageable with the free end of said bolt for preventing swinging of said bolt on its pivot.

3. A device of the class described adapted for use with a swingable closure mounted adjacent a stationary part; a plate mounted on said swingable part and comprising; a pair of spaced members projecting outwardly of said swingable part adjacent one end of said plate, the space separating said members being constricted toward the outer end thereof; a latch bolt pivotally 60 mounted adjacent one end to said stationary part and having a narrowed portion adjacent its pivoted end of sufficiently small dimension for passage through the constricted portion of said space, the remaining portion of said latch bolt 65 being of greater width than the width of the constricted portion of said space and freely slideable in said space below the constricted portion; abutment means for engaging said spaced-apart members upon swinging of said closure the 70 length of said bolt.

- of said bolt; and means carried by said plate engageable with said abutment means upon the movement of said closure to closed position for preventing swinging of said bolt on its pivot.
8. A device of the class described, adapted for use with a swingable closure mounted adjacent a stationary part, comprising: a plate mounted on the face of said closure; a pair of spaced members adjacent one end of said plate projecting outwardly therefrom, the space between said members converging toward the outer ends thereof to provide at the outer ends a constricted passage; an arm pivotally mounted at one end on said stationary part and provided adjacent its pivoted end with a narrowed portion adapted for passage through said constricted passage, the swinging of said closure to open position effecting a travel of said spaced members longitudinally of said arm, the wider portion of said arm riding in the wider portion of said space; and means carried by the free end of said arm engageable with said members for limiting slideable movement of said members along said arm in one direction.
25. 5. A device of the class described, adapted for use with a swingable closure mounted adjacent a stationary part, comprising: a plate mounted on the face of said closure; a pair of spaced members adjacent one end of said plate projecting outwardly therefrom, the space between said members converging toward outer ends thereof to provide at the outer ends a constricted passage; an arm pivotally mounted at one end on said stationary part and provided adjacent its pivoted end with a narrowed portion adapted for passage through said constricted passage, the swinging of said closure to open position effecting a travel of said spaced members longitudinally of said arm, the wider portion of said arm riding in the wider portion of said space; means carried by the free end of said arm engageable with said members for limiting slideable movement of said members along said arm in one direction; and means for normally retaining said narrowed portion out of registration with said constricted passage subsequent to the passage of said narrowed portion through said constricted passage.
6. A device of the class described, adapted for use with a swingable closure mounted adjacent a stationary part, comprising: a plate mounted on the face of said swingable closure; a pair of spaced projections extending outwardly from one end of said plate, the space between said members converging toward the outer end thereof to provide a constricted passage between said members adjacent the outer ends thereof; a bar pivotally mounted adjacent one end on said stationary part and adapted for swinging into overlying relation with said closure, said bar having adjacent its pivoted end a narrowed portion adapted for passing through the constricted passage, said bar being longitudinally moveable relatively to its pivot a predetermined distance for bringing said narrowed portion into registration with said constricted passage.
7. A device of the class described, adapted for use with a swingable closure mounted adjacent a stationary part, comprising: a plate mounted on the face of said swingable closure; a pair of spaced projections extending outwardly from one end of said plate, the space between said members converging toward the outer end thereof to provide a constricted passage between said members adjacent the outer ends thereof; a bar pivotally mounted adjacent one end on said stationary part
- and adapted for swinging into overlying relation with said closure, said bar having adjacent its pivoted end a narrowed portion adapted for passing through the constricted passage, said bar being longitudinally moveable relatively to its pivot a predetermined distance for bringing said narrowed portion into registration with said constricted passage, said bar being longitudinally moveable relatively to its pivot the length of said slot; a spring associated with said bar for normally maintaining said bar moved to a predetermined longitudinal position relatively to its pivot, said bar upon swinging on its pivot past 90 degrees engaging at its end said lock-bar and moveable against the tension of said spring.
8. In a device of the class described, a lock-bar member; a lug on said lock-bar member; a bar having an elongated slot adjacent one end; a pin projected through said slot and through said lug for pivotally mounting said bar on said lock, said bar being longitudinally moveable on its pivot the length of said slot; a spring associated with said bar for normally maintaining said bar moved to a predetermined longitudinal position relatively to its pivot, said bar upon swinging on its pivot past 90 degrees engaging at its end said lock-bar and moveable against the tension of said spring.
9. A device of the class described, adapted for use with a swingable closure mounted adjacent a stationary part, comprising: a plate mounted on said swingable closure; a pair of spaced members projecting outwardly from adjacent one end of said plate, the space between said members converging toward the outer ends thereof to provide a constricted portion; a bar pivotally mounted adjacent one end on said stationary part and swingable into said space, said bar having adjacent one end a narrowed portion for passage through said constricted space; a cross-head on the free end of said bar; and means on the opposite end of said plate for engaging said cross-head and preventing swinging of said bar upon attempted swinging of said closure.
10. A device of the class described, adapted for use with a swingable closure mounted adjacent a stationary part, comprising: a plate mounted on said closure; a pair of spaced projections extending outwardly from said plate; a bar pivotally mounted adjacent one end on said stationary part and swingable to lie in the space between said members; a cross head in the free end of the said bar engageable with said members upon a swinging of said closure a predetermined distance; and stationary means carried by said closure engageable with said cross-head for locking said bar against the swingable movement upon attempted swinging of said closure.
11. A device of the class described, adapted for use with a swingable closure mounted adjacent a stationary part, comprising: a plate mounted on said closure; a pair of spaced projections extending outwardly from said plate; a bar pivotally mounted adjacent one end on said stationary part and swingable to lie in the space between said members and longitudinally movable a predetermined distance relative to its pivot; a cross-head in the free end of said bar engageable with said projections upon a swinging of said closure a predetermined distance; abutment means carried by the opposite end of said plate, said cross-head being engageable with said abutment means; upon longitudinal movement of said bar a predetermined distance in one direction, for preventing a swingable movement of said bar upon attempted swinging movement of said closure.
12. A device of the class described, adapted for use with a swingable closure mounted adjacent a stationary part, comprising: a plate mounted on

said closure; a pair of spaced projections extending outwardly from said plate; a bar pivotally mounted adjacent one end on said stationary part and swingable to lie in the space between said members and longitudinally movable a predetermined distance relative to its pivots; a cross-head in the free end of said bar engageable with said projections upon a swinging of said closure a predetermined distance; abutment means carried by the opposite end of said plate, said cross-head being engageable with said abutment means, upon longitudinal movement of said bar a predetermined distance in one direction, for preventing a swingable movement of said bar upon attempted swinging movement of said closure; and resilient means normally resisting longitudinal movement of said bar.

13. A device of the class described adapted for use with a swingable closure mounted adjacent a stationary part and comprising: a plate mounted on said closure; one end of said plate being slotted and turned outwardly to provide a pair of spaced projections extending outwardly from said end of said plate; a bar pivotally mounted, adjacent one end, on said stationary part and adapted for swinging into overlying relation with said plate and engaging between said projections; abutment means on the free end of said bar, engageable with said projections for preventing open swinging of said swingable closure beyond a predetermined distance; engage-

ment means on the opposite end of said plate engageable, upon swinging of said closure to closed position, with said abutment means for securing said bar against swingable movement and preventing the open swinging of said closure. 5

14. A device of the class described adapted for use with a swingable closure mounted adjacent a stationary part and comprising: a plate mounted on said closure, one end of said plate being slotted and turned outwardly to provide a 10 pair of spaced projections extending outwardly from said end of said plate; a bar pivotally mounted, adjacent one end, on said stationary part and adapted for swinging into overlying 15 relation with said plate and engaging between said projections; abutment means on the free end of said bar, engageable with said projections for preventing open swinging of said swingable closure beyond a predetermined distance; an outwardly turned tongue on the opposite end of said 20 plate and engageable, upon swinging of said closure to closed position, by said abutment means for securing said bar against swingable movement and preventing the swinging of said closure, said bar being longitudinally moveable in one 25 direction into engagement with said tongue; and a spring for resisting longitudinal movement of said bar into engagement with said tongue and retaining said bar in engagement with said tongue after engagement therewith. 30
